UNITED STATES PATENT OFFICE.

THOMAS D. TAYLOR, OF PHILADELPHIA, PENNSYLVANIA.

COMBINATION DISPLAY AND VENDING CABINET.

1,414,160.

Specification of Letters Patent. Patented Apr. 25, 1922.

Application filed January 9, 1920. Serial No. 350,343.

To all whom it may concern:

Be it known that I, THOMAS D. TAYLOR, a citizen of the United States, residing at Philadelphia, in the county of Philadelphia and State of Pennsylvania, have invented 5 certain new and useful Improvements in Combination Display and Vending Cabinets, of which the following is a specification.

One object of my invention is to provide a 10 display and vending cabinet which will be so constructed that it can contain and display a comparatively great quantity of merchandise of various kinds and yet will occupy a very small amount of room. For 15 this reason my improved cabinet is particularly adapted for use in trolley cars, railroad cars, stores, factories and other places where space is limited and valuable.

Another object is to so construct and arrange 20 the parts of my improved cabinet that no floor space or standing room space is required since it can be secured within a shallow recess of any character. For example my improved cabinet is so constructed and 25 arranged that even though it is comparatively small it can contain and display for sale large quantities of cigars, cigarettes, candy, chewing gum, newspapers, magazines and other small articles.

30 A further object is to so construct my improved cabinet that the above mentioned articles can be easily removed therefrom for sale purposes; certain of the articles being arranged so that the purchaser can personally remove them from the cabinet and deposit the required amount of money in a receptacle which is provided for that purpose.

Another object is to so design and arrange 35 the parts of my improved cabinet that a large reserve stock of merchandise may be contained therein for replenishing the display spaces from time to time.

A still further object is to provide interchangeable trays which can be locked within 40 the cabinet so that either of the trays can be moved into a position to display the articles contained therein.

Another object is to make my improved 45 cabinet of a simple and durable construction and so that it will be pleasing in appearance and effectively display the articles for sale so that a person can readily see what articles are offered for sale.

These objects, and other advantageous 50 ends which will be described hereinafter, I attain in the following manner, reference be-

ing had to the accompanying drawings in which

Figure 1 is a front elevation of my improved cabinet, 60

Figure 2 is an elevation of the right end of Figure 1,

Figure 3 is an elevation of the left end of Figure 1,

Figure 4 is a sectional elevation taken on 65 the line 4—4 of Figure 1,

Figure 5 is a sectional elevation taken on the line 5—5 of Figure 3,

Figure 6 is a sectional elevation taken on 70 the line 6—6 of Figure 1,

Figure 7 is a perspective view of the cabinet shown in Figures 1 to 6 inclusive and drawn on an elongated scale,

Figure 8 is a fragmentary section showing 75 a slight modification in certain of the parts of my improved cabinet, drawn on an enlarged scale and

Figure 9 is a fragmentary perspective view showing certain of the parts made in accordance with the modification also illustrated in Figure 8. 80

Referring to Figures 1 to 7 inclusive, my improved cabinet, which may be made of wood, sheet metal or other suitable material, includes a casing 10 which has a vertically 85 extending back 11 and a front 12; said front extending parallel with the back for a distance upwardly from the base 13 and then slanting toward the back, as shown at 14. Thus the uppermost portion of the casing 90 tapers upwardly from the point 15 of the front 12 and at its top is provided with a closed hood 16; this construction being clearly shown in Figures 3, 4 and 6.

Two openings 17 and 18 are formed in 95 the front 12 directly above the base 13; the opening 18 being positioned above the opening 17. A perforated partition 19 extends through the width of the casing 10 between the openings 17 and 18 and drawers 20 and 100 21 are adapted to be inserted within the openings 17 and 18 respectively and also extend the full width of the casing 10. An upright partition 22 is formed within the width of the casing 10 and leads upwardly 105 from a partition 23 which extends above the drawer 21; said partition 22 having its forward edge, above the point 15, following the slant of the portion 14 of the casing. A number of rack partitions are interposed 110 between the upright partition 22 and the end 24 of the casing 10. These rack par-

partitions 25, as clearly shown in Figures 1 and 6, are arranged in step formation with their upper edges following the general slant of the portion 14. The bottoms of the rack partitions 25 have forwardly extending flanges 26 so that spaces 27 are provided for newspapers, magazines or the like; the arrangement being such that the stepped formation of the upper edges of these rack partitions permit the heading of the newspaper or magazine to be readily seen from the front of the cabinet. By this construction as shown in Figure 6, a chamber 28 is provided between the partitions 23 and 22 and the back 11 and end 24. This chamber can be used for storing of reserve supplies of various articles which are to be offered for sale and a door 29 is provided in the end 24 of the casing to permit access to the interior of the chamber 28. This door is preferably provided with a key lock 30. Grooved guide strips 31 are provided around the sides and bottom of the front rack partition 25 to provide an open top frame in which announcement cards or advertising signs of any character can be inserted so that they can be easily read by the public.

A partition 32 is provided within the depth of the casing as clearly shown in Figure 4; said partition 32 extending upwardly from the partition 23 and being located between the upright partition 22 and the opposite end 33 of the casing 10. This provides a space between the partition 32 and the front 12 in which is mounted two drawers 34 and 35; the front 12 being cut away to permit entrance of the drawers 34 and 35. The partition 32, at a point slightly below the level of the point 15 of the front 12, slants rearwardly substantially parallel with the portion 14 and intersects the back 11. A ledge plate 36 extends downwardly at a slant from the front 12 adjacent the point 15. Thus two compartments 37 and 38 are provided at opposite sides of the partition 32; the upper portions of each of these compartments being tapered as clearly shown in Figure 4.

The end 33 of the casing 10 has an opening 39 which is in line with the compartment 37 and said end 33 of the casing also has an opening 40 which is in line with the compartment 38. Trays 41 and 42 are adapted to be slid within the compartments 37 and 38 from the openings 39 and 40. These trays are similarly constructed and are interchangeable in view of the fact that the upper ends of the trays taper. It is merely necessary to remove the tray 42 from the compartment 38 and to turn the tray around so that its back portion is reversed and becomes the front portion when inserted within the compartment 37. Each of the trays 41 and 42 has spaces 43 which are partitioned off for small articles, such

as chewing gum and various forms of candy or the like. The bottom portion of each of the trays 41 and 42 is provided with a cup 44 into which money may be deposited by a person removing any article from the spaces 43 of the tray which is positioned within the compartment 37.

All of the drawers 20, 21, 34 and 35 are provided with key-operated locks 45 and each of the trays 41 and 42 is provided with a lock 46; the bolt of each being adapted to engage through an opening 47 in a flange 48 immediately surrounding the opening the opening 49 of the top portion of the casing directly in front of the compartment 37. The locks 46 of the trays 41 and 42 also serve to lock either of the trays when within the compartment 38. Both ends of the trays 41 and 42 are provided with handles 50 by which they may be freely pulled out of the compartments 37 and 38 when it is desired to interchange the positions of said trays as above described. Thus it is obvious that even though the tray 41 is locked within the compartment 37 that it is possible for a person to remove any of the small articles from the spaces 43 of the display tray and the money for the small articles can be dropped within the money cup 44. The lower drawers 20 and 21 are particularly adapted for holding cigars and for this reason I preferably provide a small humidor 51 in the drawer 20 and the moisture from the same is sufficient to keep the cigars in proper condition; a portion of the moisture passing through perforations 52 in the bottom of the drawer 21 and partition 19.

In the form of my invention shown in Figures 8 and 9 instead of having the trays inserted within the casing through openings in the end, a structure is provided whereby one of the trays can be slipped within the compartment 38 through the opening 49 and then permitted to drop into its position to the rear of the partition 32. The tray to be displayed can then be swung in the position as indicated by dot-and-dash lines after which it can be locked to the casing by means of a lock 53; said lock being operated by a key inserted through the key hole 53a in the front 12. The structure is such that the closed hood 16 after the tray has been inserted as above described prevents the top of the tray from being swung outwardly and the lock 53 prevents the swinging of the tray at the bottom by an unauthorized person.

It will be noted that the beveled portion 54a of the back 54 of either of the trays while within the reserve compartment 38 extends substantially parallel with the back portion 55 of the other tray when in the display compartment 37 and furthermore that the beveled portion 54a of the tray which is

within the display compartment 37 is substantially parallel with the back 11 so that the trays within the casing actually overlap in both of the forms of my invention above 5 described and thereby occupy a minimum amount of room and permit the back 11 to extend upwardly in a vertical plane. Further than this, the articles within the spaces 10 43 of the displayed tray will be in a position capable of being readily lifted from the tray by a purchaser in view of the slant of the tray and portion 14 of the casing.

While I have described my invention as taking a particular form, it will be understood 15 that the various parts of my invention may be changed without departing from the spirit thereof, and hence I do not limit myself to the precise construction set forth, but consider that I am at liberty to make 20 such changes and alterations as fairly come within the scope of the appended claims.

Having thus described my invention, what I claim as new and desire to secure by Letters Patent is:—

25 1. A cabinet of the character described including a casing having a portion slanting toward its back providing a slanting compartment open at its front; a tray fitting said compartment; said casing providing a 30 reserve compartment to the rear of said first compartment and having a portion extending above the level of the bottom of said first compartment; and a tray fitting within said reserve compartment and of substantially 35 similar construction to said first tray whereby said trays can be interchanged within said compartments.

2. A cabinet of the character described including a casing having a substantially vertical back and a front having a part extending at a slant upwardly toward said back, said casing including a space providing an upwardly and rearwardly slanting compartment having an opening in said slanting 45 portion of the front; a tray fitting said compartment, said tray having a back including

a portion substantially parallel with said slanting portion of the casing and a beveled portion substantially parallel with said back, said casing to the rear of said compartment 50 having a space providing a reserve compartment including parts extending above and below the bottom of said first compartment; and a tray fitting said reserve compartment and of substantially similar construction to 55 said first tray, the beveled portion of the tray within said reserve compartment extending substantially parallel to the portion of the back of said tray which is parallel to said slanting part of the casing. 60

3. A casing including an upright back with a forwardly extending hood at its top and a ledge portion below and forward of the top of the hood; a removable tray having a beveled back adjacent its top end to 65 permit said top end to be inserted under the hood with the beveled portion of the back substantially parallel with the upright back of the casing, the bottom end of said tray being shaped to be positioned over said ledge 70 portion of the casing; and means for locking the tray, in said position, to the casing.

4. A casing including an upright back with a forwardly extending hood at its top and a slanting ledge portion below and forward of the top of the hood; and a removable tray having a beveled back adjacent its top end to 75 permit said top end to be inserted under the hood with the beveled portion of the back substantially parallel with the upright back of the casing, the bottom end of 80 said tray being substantially rectangular and adapted to be positioned over said slanting ledge portion.

In testimony whereof I have signed my 85 name to this specification in the presence of two subscribing witnesses.

THOMAS D. TAYLOR.
